TIME-INTERVAL MECHANISM.

Application filed October 14, 1920. Serial No. 416,891.

This invention relates to improvements in time-interval mechanism for securing successive operations of the mechanism at certain predetermined time intervals apart.

It is the object of the present invention to provide a mechanism for this purpose in which the time intervals for such operations may be manually varied as desired and in which such operations are effected automatically and repeated as many times as desired.

In the accompanying drawings—

Figure 1 is a top plan view, Figure 2 a side elevation, and Figure 3 a bottom plan view of a time interval apparatus embodying the present invention in its preferred form;

Figure 4 is an end view of the apparatus looking toward the left of Figure 1;

Figure 5 is a vertical section on the line 5 of Figure 4;

Figure 6 is a horizontal section on the line 6 of Figure 5;

Figure 7 is a detail of portions of the circuit making and breaking mechanism of the apparatus;

Figure 8 is an end view of the same looking toward the left of Figure 7;

Figure 9 is a diagrammatic view illustrating the arrangement of the different circuits in the apparatus.

In said drawings A represents a continuously running motor, such as an ordinary clock mechanism, B time interval mechanism proper of the present invention controlled thereby, and C a member, such as a bell, controlled or actuated by the time interval mechanism; all of these parts, with their connections, being mounted upon a suitably supported table D.

The clock mechanism A needs no description except to point out that it actuates an escapement the members 1, 2, 3 of which in turn periodically swing a contact maker 4 to and fro so as to, in each second, twice engage a stationary contact 5 and thus twice close the circuit of the time interval apparatus proper.

The time interval apparatus proper comprises a dial 6 fixed to table D and having thirty "seconds" sub-division, each in turn divided into half seconds. With this dial coacts a manually adjustable pointer arm 7 fixed to a shaft 8 journaled in and projecting downwardly through registering open-

ings in table D and in a hub 9 of a bracket 10 secured to the under side of the table. At a point below hub 9 the shaft 8 has fixed to it a radially projecting arm 11 provided at its outer end with a stop 12, for a purpose which will later on appear. As this arm 11 and pointer arm 7 are both fixed to shaft 8 it follows that as the pointer arm is turned to a selected position along dial 6 the arm 11 will swing with it and its stop 12 be adjusted to a corresponding position 65 on the under side of table D. Dial 6 is provided with holes 13 and pointer arm 7 with a spring pressed pin 14 for retaining said arm 7 and arm 11 in the positions to which they may be adjusted. 70

The time interval mechanism is also provided with a toothed wheel 15 and a pawl 16 for actuating it and with a retaining pawl 17 engaging said wheel to prevent retrograde movement thereof. Pawl 16 is 75 pivotally mounted in the outer end of the pivotally mounted armature 18 of a magnet 19 so that each time said armature is attracted wheel 15 will be turned one tooth. Armature 18 is held in retracted position by 80 a spring 20, and pawls 16, 17 in engagement with wheel 15 by a spring 21 between the two pawls. Pawl 16 performs simply the function of rotating wheel 15 step-by-step, while pawl 17 performs not only the function of preventing retrograde movement of 85 said wheel but also acts as a circuit closer, in connection with a pair of insulated clips 22, 23, for a purpose which will presently be stated. 90

The energization of magnet 19 for the actuation of pawl 16 and step-by-step movement of wheel 15 is effected from a battery 24 through the following circuit controlled by contacts 4, 5: negative of battery 24, 95 wire 25, contacts 4, 5, wires 26, 27, 28, winding of magnet 19, wires 29, 30 to the positive of battery 24. This circuit is closed each time (in other words, every half second) escapement contact 4 engages stationary contact 5 so that, in each half second, wheel 15 is turned one tooth by pawl 16, or 120 teeth per minute. 100

The time interval mechanism thus far described is provided with means whereby at any selected or predetermined point in the step-by-step movement of wheel 15 the bell C will be actuated; the means provided 105

being such that the ringing of the bell may be repeated, at such point, as often as desired while wheel 15 rotates. For this purpose there is provided an arm or trigger 31 secured to a sleeve 32, which is in turn mounted on a stud 33 and journaled in a hub 34 fixed in one end of a plate spring support 35 the opposite end of which is fixed to a standard 36 projecting downwardly from the bracket 10. The sleeve 32 is movable upwardly and downwardly, in the former direction by its spring support 35 and in the latter direction by an arm 37, one end of which engages a flange or washer 15 at the lower end of the sleeve 32 and the other end of which is secured to the armature 38 of a magnet 39. The trigger 31 is provided with an upward projection or tooth 40 which is held, by plate spring 35, in engagement with the teeth of wheel 15, so that as said wheel is rotated by pawl 17 said arm 31 will rotate with it. The hub 34 contains a coiled spring 41, one end of which is secured to said hub or the spring support 35 and the other end of which engages the sleeve 32 fixed to said arm 31, with the result that as the arm 31 is thus rotated by the wheel 15 the spring 41 will be wound up and tend to move the arm 31 in the opposite direction. Such movement, however, is prevented until the wheel 15 has been rotated a number of teeth or steps predetermined by the position to which the pointer arm 7, and arm 11 with its stop 12, moving therewith, are manually adjusted. When the wheel has been rotated such predetermined number of steps or teeth the projection 40 of arm 31 will engage the wheel retaining end of pawl 17 and move it outwardly, thus forcing the other end of said pawl between contact clips 22, 23 and closing the following circuit through magnet 39: negative of battery 24, wire 25, contacts 4, 5, wires 26, 27, 42, contact 22, pawl 17, contact 23, wires 43, 51, winding of bell magnet 52, wires 53, 47, 30 to the positive pole of battery 24. When the pawl 17 is freed from the clips 22, 23, and the contacts 4 and 5 separate, the magnet 39 is de-energized, the armature 38 is retracted by its spring 54 and, when so retracted, will permit plate spring 35 to move arm 31 toward wheel 15 to re-engage tooth 40 thereof with said wheel.

Simultaneously with the engagement of the pawl 17 with the contact clips 22, 23 at the end of the forward movement of the arm 31 the bell C will be rung from battery 24 through the following circuit: negative of battery 24, wire 25, contacts 4, 5, wires 26, 27, 42, contact 22, pawl 17, contact 23, wires 43, 51, winding of bell magnet 52, wires 53, 47, 30 to the positive of battery 24. When the pawl 17 is freed from the clips 22, 23, and the contacts 4 and 5 separate, the magnet 39 is de-energized, the armature 38 is retracted by its spring 54 and, when so retracted, will permit plate spring 35 to move arm 31 toward wheel 15 to re-engage tooth 40 thereof with said wheel.

In other words, if, for example, the pointer arm 7 be adjusted at "20" on the indicator dial 6 the wheel 15 will be rotated forty teeth. At the beginning of its rotation the projection 40 of arm 31 will rest against the stop 12 of arm 11 and as the wheel 15 is rotated the arm 11, because of its engagement through its projection or tooth 40 with said wheel, will rotate therewith until the wheel has been moved forty teeth. The projection or tooth 40 of the arm 31 will then engage the pawl 17 and move the free end thereof between the contact clips 22, 23. The engagement of the pawl 17 with these contacts will close the bell circuit just described, thus causing the bell C to be rung, and will, at the same time, through the energization of magnet 39, release the projection or tooth 40 from engagement with wheel 15 and permit the spring 41 to turn said arm in the opposite direction until it again engages the projection or tooth 12 of the arm 11, which prevents its further movement in that direction. This operation of the arm 31, and therefore the actuation of the bell C, will continue to be repeated so long as the wheel 15 is rotated and pointer arm 7 remains at the graduation "20" on the dial 6. If the pointer arm 7 be changed to "15" or any other graduation of the dial the operation of the arm 31, and therefore the ringing of the bell C, will be the same as 130

just described except that it will take place when the wheel 15 has been moved thirty teeth; and so on, the bell being rung repeatedly by the time interval apparatus, with any desired time interval between the ringings thereof that may be predetermined by the adjustment of arm 7.

What is claimed is:—

1. The combination with a motor and a contact maker periodically actuated thereby, of a circuit, including a magnet, periodically closed by said contact maker, a step-by-step movable member controlled by said magnet, a trigger normally engaged with and movable by said member, means controlled by the trigger and by said contact maker for repeatedly disengaging it from said member at predetermined points in the member's movement, means for moving the trigger when so disengaged in the opposite direction to the member's movement to return the trigger to its initial position during the period between two successive operations of said contact maker, an adjustable stop for limiting the trigger's movement in this direction and predetermining the points in the member's movement at which it shall be disengaged therefrom, and manually controlled means for adjusting said stop.
2. The combination with a motor and a contact maker periodically actuated thereby, of a circuit, including a magnet, periodically closed by said contact maker, a step-by-step movable member controlled by said magnet, a trigger normally engaged with and movable by said member, a magnet for repeatedly effecting its disengagement from

said member at predetermined points in the member's movement, a circuit controlling said magnet and in turn controlled by the circuit maker aforesaid and said trigger, means for moving the trigger when so disengaged in the opposite direction to the member's movement, an adjustable stop for limiting the trigger's movement in this direction and predetermining the points in the member's movement at which it shall be disengaged therefrom, and manually controlled means for adjusting said stop.

3. The combination with a motor and a contact maker periodically actuated thereby, of a circuit, including a magnet, periodically closed by said contact maker, a step-by-step movable member controlled by said magnet, a spring pressed trigger normally engaged with and movable by said member, a magnet for repeatedly effecting its disengagement from said member at predetermined points in the member's movement, a circuit controlling said magnet and in turn controlled by the circuit maker aforesaid and said trigger, a spring for moving the trigger when so disengaged in the opposite direction to the member's movement, an adjustable stop for limiting the trigger's movement in this direction and predetermining the points in the member's movement at which it shall be disengaged therefrom, and manually controlled means for adjusting said stop.

In testimony whereof, we have hereunto set our hands.

GEORGE S. TIFFANY.
THEODORE W. DENISON.
